UNITED STATES PATENT OFFICE.

HANS FRITZ, OF MODLING, NEAR VIENNA, AUSTRIA, ASSIGNOR OF ONE-HALF TO
ENGELBERT KLEINHENZ, OF KIRCHGASSE, WIESBADEN, GERMANY.

HOLLOW WALL.

Application filed May 6, 1925. Serial No. 28,458.

To all whom it may concern:

Be it known that I, HANS FRITZ, a citizen of the Republic of Austria, residing at Modling, near Vienna, Austria, have invented certain new and useful Improvements in Hollow Walls, of which the following is a specification.

This invention relates to improvements in hollow walls composed of a framework 10 which is covered with plates.

The present invention consists in the connection between the plates of each wall forming the hollow wall, at the back side the plates being provided with ribs or 15 grooves and further the connection between the oppositely disposed walls of the hollow wall is carried out by tensioning members arranged in pairs and into the grooves of which the ribs of the plates are adapted to 20 engage and which are tightened up with one another in known manner.

The individual plates essentially are formed by a skeleton or netted member, which is produced of ledges or strips over- 25 lapping one another and which at least on one side is covered with a suitable material such as wood, artificial stone, asbestos slates, mortar, gypsum, plaster and the like.

Owing to the formation of the plates by 30 a netting or skeleton and the interengagement of its ledges at the transecting places, the entire cross-sectional area of the said ledges appear as cross-grained wood at the edges of the plates. On placing the plates 35 side by side always cross-grained woods are abutting, so that any alteration of the wall in consequence of shrinkage or contraction is rendered impossible.

A further advantage of the netted member 40 consists in that gaps are formed in the lateral edges of the plates between the bars of the netted member, suitably shaped pins being disposed in the said gaps, which extend beyond the edge of the plate and when 45 placing the same side by side engage into the gaps of the adjacent plate, thus producing a homogeneous unit, as the plates interengage and are connected with respect to one another and may be glued together 50 during the erection.

One mode of carrying out the present invention is shown by way of example on the accompanying drawing.

At certain convenient distances, posts 2 55 are mounted in the longitudinal recess of a

grooved base 1 and are furnished with wedge-shaped slots 3. The individual construction-members of the walls are formed of plate-like members and at their inner sides are provided with wedge-shaped extensions 5, which serve as a means for securing wedge-shaped members 6, the latter being connected with one another by a tensioning or connecting member 7 in case of connecting with one another the said plates, 60 or if the plates are secured to the post 2 the said members 6 are secured to a member 8, engaging the wedge-shaped slot 3 of the said post. The tensioning members 7 or the members 8 secured in the post are furnished 65 with slots through which cotters 9 are driven, the latter pressing the wedge-shaped members 6 against the extensions 5 and thus form a stable connection between the plates or for securing the same to the posts. Preferably the plates are disposed above each other in stepped manner like bricks. In order to bind or connect the individual layers, the edges of the plates are provided with inwardly projecting, undercut guide-grooves into which ledges 10 are driven. The latter extend from the middle of the plates of one layer to the middle of the plates of the second layer, so that in the 70 present case always two layers of plates, which are not immediately adjacent to each other, are connected or bound with one another. Thus the ledges 10 form a reliable means for closing-up the space between the contacting edges of the plates. 75

Of course, if desired, the extensions 5 of the plates may be formed by furnishing the plate with a conveniently shaped groove, the outer walls of which result in a rib, which does not extend beyond the plane of the 80 plate:

The plate is provided with a skeleton or netting, formed of bars 4 of the same thickness, which overlap each other at the crossing places, so that the entire cross-sectional area appears at the edges. The netting 4 is covered at both sides with wooden linings or boards 11 or the like, which impart a great rigidity to the netting. If desired plates pressed of a suitable material may be substituted for the boards 11, the said plates being provided, at the inside, with elevated parts corresponding to the holes of the netting and filling-up the said holes if the plates are connected with the netting. The 100 105 110

outsides of the linings may be covered with a facing 12 of artificial stone or the like. At the borders of the plates the netting appears as a comb-shaped member, as the ends 5 of the bars 4 project beyond the outermost bars for half the width of a hole. Thus it is rendered possible to dispose block 13 into the holes, formed between two bars, the said blocks projecting beyond the end of the 10 plate and engaging the holes of the adjacent plates, and in this manner produce a good connection between the plates.

The hollow spaces of the netting, not only mean a saving of material, but also are 15 a very good means of isolation.

Any movement of the wood is rendered impossible, as the grains of the wood are disposed horizontally and vertically and thus a shrinkage of the wood in any direction 20 is quite impossible. The distance between the bars of the netting corresponds to certain measurements of the plate, so that at any desired division of the plate always cross-grained wood rests on cross-grained 25 wood.

I claim:

1. A hollow wall comprising in combination, plates forming the walls of the said hollow wall and provided with rib-shaped 30 projections at the back-side, connecting members arranged in pairs for connecting the plates of each wall of the said hollow wall and for connecting the oppositely disposed walls of the hollow wall, and 35 grooves in the said connecting members adapted to be engaged by the said projections.

2. A hollow wall comprising in combination, plates forming the walls of the said 40 hollow wall and provided with grooves at the back-side, connecting members arranged in pairs for connecting the plates of each wall of the said hollow wall and for connecting the oppositely disposed walls of the 45 hollow walls, and rib-shaped projections on the said connecting members adapted to engage the said grooves provided in the plates.

3. A plate for constructing hollow walls 50 composed of transecting bars which overlap one another at the crossing places and the ends of which extend beyond the crossing places to form a skeleton, and a wooden lining covering the sides of the said skeleton.

4. A hollow wall comprising in combination, plates forming the walls of the said 55 hollow wall and provided with rib-shaped projections at the back-side, each plate being composed of transecting bars which overlap 60 one another at the crossing places and the ends of which extend beyond the crossing places to form a skeleton, a wooden lining covering the sides of the said skeleton connecting members arranged in pairs for connecting the plates of each wall of the said 65

hollow wall and for connecting the oppositely disposed walls of the hollow wall, and grooves in the said connecting members adapted to be engaged by the said projections.

5. A hollow wall comprising in combination, plates forming the walls of the said hollow wall and provided with grooves at the back-side, each plate being composed of transecting bars which overlap one another 70 at the crossing places and the ends of which extend beyond the crossing places to form a skeleton, a wooden lining covering the sides of the said skeleton connecting members arranged in pairs for connecting the plates of each wall of the said hollow wall and for connecting the oppositely disposed walls of the hollow walls, and rib-shaped projections on the said connecting members adapted to engage the said grooves provided in the plates.

6. A plate for constructing hollow walls composed of transecting bars which overlap one another at the crossing places and the ends of which extend beyond the crossing places to form a skeleton, a wooden lining covering the sides of the said skeleton and a facing covering the outside of the said lining.

7. A hollow wall comprising in combination, plates forming the walls of the said hollow wall and provided with rib-shaped projections at the back-side, each plate being composed of transecting bars which overlap one another at the crossing places and the ends of which extend beyond the crossing places to form a skeleton, a wooden lining covering the sides of the said skeleton, a facing covering the outside of the said lining, connecting members arranged in pairs for connecting the plates of each wall of the said hollow wall and for connecting the oppositely disposed walls of the hollow wall, and grooves in the said connecting members adapted to be engaged by the said projections.

8. A hollow wall comprising in combination, plates forming the walls of the said hollow wall and provided with grooves at the back-side, each plate being composed of transecting bars which overlap one another at the crossing places and the ends of which extend beyond the crossing places to form a skeleton, a wooden lining covering the sides of the said skeleton, a facing covering the outside of the said lining, connecting members arranged in pairs for connecting the plates of each wall of the said hollow wall and for connecting the oppositely disposed walls of the hollow walls, and rib-shaped projections on the said connecting members adapted to engage the said grooves provided in the plates.

In testimony whereof I affix my signature,
HANS FRITZ.
